UNITED STATES PATENT OFFICE.

LOUIS DUSSART AND EDWARD COLIN, OF KINCAID, ILLINOIS.

SLIDE-RAIL BRACE.

1,318,058.

Specification of Letters Patent.

Patented Oct. 7, 1919.

Application filed June 14, 1919. Serial No. 304,312.

To all whom it may concern:

Be it known that we, LOUIS DUSSART and EDWARD COLIN, citizens of the United States and the French Republic, respectively, both residing at Kincaid, in the county of Christian and State of Illinois, have invented certain new and useful Improvements in Slide-Rail Braces, of which the following is a specification, reference being had to the accompanying drawings.

This invention relates to slide rails such as are used to form extensions of tracks in mines.

In mining tunnels, more or less permanent tracks are laid leading from a position more or less adjacent the breast of the work, upon which tracks the cars receiving the ore are disposed. Slidably engaged with these permanent rails are slide rails which, as the cutting continues, are shifted relative to the permanent rails so as to extend, as it were, the permanent rails toward the breast or face. These sliding rails are not held firmly in position, and indeed are usually held upon the last tie of the permanent track by a pair of spikes and by their engagement with the main or permanent rails of the track. As a consequence of this, these sliding rails will often be diverged from each other or converged toward each other so that the sliding track becomes either too wide or too narrow and the mine car gets off the track. The thrust of this car is often the cause of the sliding rails shifting laterally or being forced apart.

The object of this invention is to provide means for holding the outer ends of the slide rails from moving toward or away from each other, and as the inner ends of the slide rails are held by the spikes before referred to, it is obvious that the rails will be held in parallel position, that is in gage.

A further object of the invention is to provide a brace which will engage the outer ends of the slide rails and hold them to proper gage, and to provide a brace which, being formed in two parts, may be adjustable as to length, inasmuch as there is no standard width or gage for these slide rails or for the tracks in different mines.

The invention is illustrated in the accompanying drawings, wherein:—

Figure 1 is a top plan view of a portion of a main track showing our invention applied to the sliding rails thereof, the brace being partly in section;

Fig. 2 is an end elevation of the construction shown in Fig. 1; and

Fig. 3 is a section on the line 3—3 of Fig. 1.

Referring to these drawings, it will be seen that our device comprises a brace consisting of two sections 10 and 11. Each section comprises a head and a shank, which head 12 is formed with a slot 13, which has the form of a cross section of a slide rail. This slide rail has the form of an ordinary track rail set on its side so that the flanges extend vertically instead of horizontally. One of the sections, as for instance the section 11, has a hollow shank. The other section has a shank 14 of sufficiently small size to be inserted in the hollow shank 15 of the section 11, and both of these shanks are perforated, as at 16, for the passage of a locking pin 17. This locking pin is attached to one of the members 10 or 11 by means of a chain 18.

The slide rails 19, as before remarked, are like the main rails 20 of the track, but are disposed with their flanges extending vertically and with the head of each slide rail disposed between the base and the head of a main rail (see Fig. 3). These slide rails are held in position by one or more spikes 21 so that they may be shifted longitudinally from time to time as desired. The slide rails 19 at one or both ends are formed with perforations 22 through the web, and pins 23 are provided connected to each head 12 by means of a chain 24, which chains are adapted to be inserted in the perforations 22 to limit the outward movement of the brace with relation to the slide rails.

The use of this device will be obvious from what has gone before. It is simply engaged with the outer ends of the slide rails 19 and held in place by the pins 23. Thereafter the slide rails may be pulled out as much as desired and they will always be held in parallel relation. It will be seen that this brace also constitutes a stop limiting the movement of the cars in one direction upon the slide rails. The brace will, of course, be made of iron or steel, and may be of any desired size and expandible or contractible to any desired length. The device is very simple, can be readily applied, and prevents derailing of the cars and thus prevents the loss of time due to replacing the cars on the track.

Furthermore, this slide-rail brace, by preventing the derailing of cars on the slide rails, eliminates danger of injury to operators incident to lifting the cars to replace them on the track, and the loss of time incident to such replacement.

We claim:—

1. In a mine track, the combination with main rails and slide rails disposed inward 10 of the main rails and slideable thereon for longitudinal movement relative thereto, of a brace engaging the slide rails at their outer ends remote from the main rails and holding said slide rails from relative lateral 15 movement, said brace being formed in two relatively adjustable sections.
2. A brace for the slide rails of mine tracks composed of two sections having sliding engagement with each other, of 20 means for holding the sections in any longitudinally adjusted relation, each section at its end being formed with an opening having the same form as the cross section of the slide rail and into which opening the 25 slide rail fits snugly, and means for holding the brace of said slide rails.
3. A brace for the slide rails of mine tracks formed in two sections, each section having a head slotted for the passage of 30 the slide rail, and a shank, the shank of one head being hollow and the shank of the other head having telescopic engagement with the first named shank, both of said shanks being perforated, and a pin engag- 35 ing in the perforations of said shanks to hold the shanks longitudinally adjusted with relation to each other.
4. In a mine track, the combination with the main rails and slide rails disposed in- 40 ward of the main rails and having longi-

tudinal movement relative thereto, of a brace for the outer ends of the slide rails, said brace having at its ends slots through which the outer ends of the slide rails are disposed, and means for preventing the 45 brace from being disengaged from the slide rails.

5. In a mine track, the combination with the main rails and slide rails disposed inward of the main rails and having longitudinal movement relative thereto, of a brace for the outer ends of the slide rails, said brace having at its ends slots through which the slide rails are disposed, and pins 50 flexibly connected to the brace, the slide 55 rails being formed with perforations in which said pins may be disposed to thereby prevent the slipping off of the brace.

6. The combination with the main rails of a mine track, rails disposed inward of 60 the main rails and having channels in their upper faces, the inner wall of each channel being coincident with the lateral face of the head of the main rail, means for holding the slide rails with their inner ends 65 against the side faces of the main rails but permitting said slide rails to be longitudinally shifted, and members operatively detachably engaging those ends of the slide rails remote from the main rails and holding the outer ends of the slide rails from 70 lateral movement.

In testimony whereof we hereunto affix our signatures in the presence of two witnesses.

LOUIS DUSSART.
EDWARD COLIN.
